ATTORNEY.

UNITED STATES PATENT OFFICE

SAMUEL S. ROBINSON, OF PASSAIC, NEW JERSEY

METHOD AND APPARATUS FOR LAYING STRIP MATERIAL

Application filed August 6, 1930. Serial No. 473,355.

This invention relates to apparatus for use in laying strips of roofing or other material contained on rollers, and to the application of a liquid cement or a compound having adhesive properties to the surface of the strip material which is to be applied to the roof, as well as to applying said liquid adhesive to the upper surface of the first named strip when laid upon the roof to secure a second strip thereto; and the object of the invention is to provide an apparatus of the class and for the purpose specified comprising a frame with means for supporting and guiding a roll of strip material in said frame, said frame having rollers or other anti-frictional devices, permitting the free movement of the frame over a surface in the application of the strip material from said roller thereto; a further object being to provide a container movably supported in said frame over said roll and bearing thereon, in which container the liquid adhesive or cement is supported and by means of which weight is applied to the roll of strip material in its application to the surface over which the apparatus passes, said container having an anti-frictional roller on its under surface adapted to bear upon said roll; a further object being to provide means for controlling the discharge of the liquid from said container in its application to one side surface of the strip material on said roll; a further object being to provide means for discharging said liquid onto the strip material after it has been laid upon said surface, a single manually operated means being employed to control both of said liquid discharges; a further object being to provide means for supporting another roll of strip material in connection with the frame of the apparatus so as to apply said strip onto the first named strip and the liquid coating applied thereto; a still further object being to provide splash shields for confining the application of the liquid onto said strip material; and with these and other objects in view, the invention consists in an apparatus of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a front view of my improved apparatus with part of the construction removed and broken away; and,

Fig. 2 is a transverse section on the line 2—2 of Fig. 1.

In practice, I provide a suitable frame consisting of substantially rectangular side plates 5 and 6 joined at the upper corners by connecting rods 7, and at the lower corners by rods 8, the latter rods projecting through the plates 5 and having rollers 9 arranged thereon to support the frame upon a suitable surface and to permit free movement of said frame thereover.

Each of the plates 5 and 6 is provided centrally thereof with vertical apertures 10 opening through the lower ends of said plates and in which the rod 11 of a roll of strip material 12 is adapted to operate in such manner that the roll 12 rests upon the surface over which the frame is moved, said roll being arranged within and between the side plates. Movable supported within the side plates 5 and 6 and the rods 7 of the frame is a tank 13 or container having an opening at one side thereof as seen at 14, which opening is controlled by a cover 15 hinged as seen at 16; and through this opening, fluid such as a suitable cement, tar, pitch or other adhesive compound 17 is adapted to be placed in said container. At spaced intervals, a plurality of beveled or anti-splash walls 18 are arranged, said walls terminating short of the top and bottom of the container as seen. Arranged longitudinally of the bottom of the container is an elongated discharge spout or nozzle 19, in connection with which three apertures 20 opening into the container 13 communicate, the apertures 20 being controlled by valves 21 actuated through valve rods 22 extending through guides 23 in the top of the container. The protruding ends of said rods are coupled together by a bar 24 engaging heads 25 on said rods.

The valves 21 are normally held in closed position by gravity and are adapted to be raised into open position by levers 26 pivoted to the top of the container 13 as seen at 27, 5 said levers being coupled with other levers 28 as seen at 29, the levers 28 being pivoted to the container as seen at 30 and cooperating with a bar 31 disposed beneath the heads 32 of other valve rods 33 passing through guides 10 34 in the top of the container and terminating at their lower ends in valves 35 controlling passages opening into a pipe 36, connected to a transversely disposed discharge pipe or nozzle 37 through which the fluid 17 may be dis- 15 charged.

It will be noted on a consideration of Fig. 1 of the drawings that three valves 21 and their companion parts are employed, whereas two valves 35 and their companion parts are 20 employed, and two sets of the levers 26-28 are arranged one adjacent each side portion of the container, and the connected ends 29 of these levers have attached thereto cords or wires 38 which pass around pulleys 39 25 and are connected with a manually controlled operating rod 40 movable in keepers 41 arranged on the top of the container 13. By pulling outwardly on the rod 40, the adjacent ends of the levers 26 and 28 will be 30 moved downwardly, thus raising the outer ends of said levers, and moving the valves 21 and 35 into open position to discharge the fluid 17 from the container. The valves 21 and 35 may be adjustable with respect to the 35 apertures or passages which they control so as to insure the seating of said valves to control the discharge of liquid from the tank.

It will be noted on a consideration of Fig. 1 of the drawings, that the nozzle 19 extends 40 throughout substantially the full width of the frame, and is slightly less in length than the length of the roll 12 of strip material, whereas the nozzle tube 37 is shorter. Arranged adjacent the nozzle 19 is a liquid 45 spreader in the form of a plate 42, hinged as seen at 43 and having a spring 44 for normally supporting the plate 42 in engagement with the roll 12, thus confining the fluid discharged from the nozzle 19 to the strip 50 material on said roll. A similar spreader 45 is pivoted to a bracket 46 attached to a reinforcing frame member 47 arranged adjacent the lower end of and coupling the side walls 5 and 6 of the frame. The spreader 55 45 serves to spread the fluid discharged from the nozzle tube 37 over the upper surface of the strip, unravelled from the roll 12. A plurality of hooks 48 are supported in connection with the member 47 above the spreader 45 in connection with which loops 49 on a supplemental frame 50 are adapted to operate, the frame 50 consisting of front, back and side wall members within and between the central portion of which is supported a 55 bar 51 on which another roll of strip mate-

rial 52 is mounted. It will be noted on a consideration of Fig. 2 of the drawings that the outer end portion 50a of the frame 50 is inclined upwardly so as to permit the frame to drop into juxtaposition to the surface over 70 which the roll 52 passes, until said roll has been fully consumed, the hooks 48 and loops 49 acting as a flexible hinge, permitting the aforementioned operation.

Arranged upon the lower surface of the 75 tank 13 centrally of the opposite sides thereof are anti-frictional rollers 53 which support the tank or container 13 upon the roll 12. It will thus be seen that the weight of this container and its contents is constantly resting upon the roll 12 so as to securely and firmly lay the strip material of said roll upon the surface over which the apparatus passes. The rods 7 preferably have tubes 7a rotatably mounted thereon to provide for the free and easy vertical movement of the container 13 in said frame as the roll of strip material is consumed, it being understood that this container is free to move downwardly into the lower portion of the frame. Coupled with 80 the frame member 47 opposite the attachment of the frame 50 therewith is a yoke-shaped operating handle 54 whereby the apparatus may be moved over a suitable surface. It is also preferred that the container have 85 handle members 55 at each side thereof, by means of which said container may be raised in the frame in the application of placing a new roll of strip material therein.

My invention relates primarily to the laying of roofing, felt, paper or other strip material normally contained in rolls, upon a roof or upon a surface of any kind or class and also in the application of a liquid to one or both faces of said material to secure the same to 100 the said surface, and if desired, to secure another strip upon the first named strip. While this is the preferred use of the invention, it will be understood that my improved apparatus may be used in laying floor coverings of various kinds and classes or in applying strip material of any desired width and texture to the surface over which the apparatus passes, it being understood that the size and dimensions of the apparatus 105 will depend entirely upon the material in connection with which the same is employed; and various other changes in and modifications of the construction herein disclosed may be made within the scope of the appended 110 claims without departing from the spirit of my invention or sacrificing its advantages.

Having fully described my invention, what I claim as new and desire to secure by Letters Patent, is:—

1. A machine of the class described comprising a frame, means for supporting said frame to permit its free movement over a predetermined surface, means for supporting a roll of strip material in said frame 115

- and upon the surface over which the frame passes, means for applying an adhesive substance to the strip material of said roll in the operation of laying the same on said surface, and said last named means comprising a liquid storage tank movably supported in the frame and resting upon said roll. 5
2. A machine of the class described comprising a frame, means for supporting said frame to permit its free movement over a predetermined surface, means for supporting a roll of strip material in said frame and upon the surface over which the frame passes, means for applying an adhesive substance 10 to the strip material of said roll in the operation of laying the same on said surface, said last named means comprising a liquid storage tank movably supported in the frame and resting upon said roll, and means for controlling the discharge of liquid from said 15 tank. 20
3. A machine of the class described comprising a frame, means for supporting said frame to permit its free movement over a predetermined surface, means for supporting a roll of strip material in said frame and upon the surface over which the frame passes, means for applying an adhesive substance to the strip material of said roll in the operation 25 of laying the same on said surface, said last named means comprising a liquid storage tank movably supported in the frame and resting upon said roll, means for controlling the discharge of liquid from said 30 tank, and the liquid discharge of said tank comprising an elongated nozzle arranged longitudinally of and adjacent the periphery of said roll. 35
4. An apparatus of the class described comprising a frame in which a roll of strip material is free to pass and to move toward said surface in the removal of the strip material therefrom, means for guiding said roll in its movement with respect to said frame, a liquid 40 storage chamber in said frame, and means for discharging a liquid therefrom onto the outer surface of the strip material on said roll prior to laying the same on said surface. 45
5. An apparatus of the class described comprising a frame in which a roll of strip material is free to pass and to move toward said surface in the removal of the strip material therefrom, means for guiding said roll in its movement with respect to said frame, a liquid 50 storage chamber in said frame, means for discharging a liquid therefrom onto the outer surface of the strip material on said roll prior to laying the same on said surface, and other means for discharging liquid material 55 onto the upper face of the strip laid on said surface. 60
6. An apparatus of the class described comprising a frame in which a roll of strip material is free to pass and to move toward said surface in the removal of the strip material 65
- therefrom, means for guiding said roll in its movement with respect to said frame, a liquid storage chamber in said frame, means for discharging a liquid therefrom onto the outer surface of the strip material on said roll prior to laying the same on said surface, other means for discharging liquid material onto the upper face of the strip laid on said surface, and manually operated means for controlling the discharge of liquid from both of said discharging means. 70
7. An apparatus of the class described comprising a frame in which a roll of strip material is free to pass and to move toward said surface in the removal of the strip material therefrom, means for guiding said roll in its movement with respect to said frame, a liquid storage chamber in said frame, means for discharging a liquid therefrom onto the outer surface of the strip material on said roll prior to laying the same on said surface, other means for discharging liquid material onto the upper face of the strip laid on said surface, manually operated means for controlling the discharge of liquid from both of said discharging means, and means for movably supporting a second roll of strip material in connection with said frame in such manner as to lay the strip of the second named roll upon said first named strip simultaneously in 80 the movement of said frame over said surface. 85
8. An apparatus of the class described comprising a frame in which a roll of strip material is free to pass and to move toward said surface in the removal of the strip material therefrom, means for guiding said roll in its movement with respect to said frame, a liquid storage chamber in said frame, means for discharging a liquid therefrom onto the outer surface of the strip material on said roll prior to laying the same on said surface, other means for discharging liquid material onto the upper face of the strip laid on said surface, manually operated means for controlling the discharge of liquid from both of said discharging means, means for movably supporting a second roll of strip material in connection with said frame in such manner as to lay the strip of the second named roll upon said first named strip simultaneously in 90 the movement of said frame over said surface. 95
9. An apparatus for laying strip material onto a predetermined surface, said strip material being contained on a roll, means for supporting said roll in the apparatus in such manner as to rest upon the surface over which the apparatus is moved in the operation of laying said strip material, and means in said apparatus supported on said roll for apply- 100

ing pressure thereto to facilitate the laying of said strip on said surface.

10. An apparatus for laying strip material onto a predetermined surface, said strip material being contained on a roll, means for supporting said roll in the apparatus in such manner as to rest upon the surface over which the apparatus is moved in the operation of laying said strip material, means in said apparatus supported on said roll for applying pressure thereto to facilitate the laying of said strip on said surface, and means for applying an adhesive substance to that face of the strip arranged adjacent said surface to secure said strip thereto.

11. An apparatus for laying strip material onto a predetermined surface, said strip material being contained on a roll, means for supporting said roll in the apparatus in such manner as to rest upon the surface over which the apparatus is moved in the operation of laying said strip material, means in said apparatus supported on said roll for applying pressure thereto to facilitate the laying of said strip on said surface, means for applying an adhesive substance to that face of the strip arranged adjacent said surface to secure said strip thereto, and other means for applying a suitable adhesive to the upper face of said strip after it has been applied to said surface.

12. An apparatus for laying strip material onto a predetermined surface, said strip material being contained on a roll, means for supporting said roll in the apparatus in such manner as to rest upon the surface over which the apparatus is moved in the operation of laying said strip material, means in said apparatus supported on said roll for applying pressure thereto to facilitate the laying of said strip on said surface, means for applying an adhesive substance to that face of the strip arranged adjacent said surface to secure said strip thereto, other means for applying a suitable adhesive to the upper face of said strip after it has been applied to said surface, and means for movably supporting another roll of strip material in connection with the apparatus to be laid onto the first named strip in the progress of the apparatus over said surface.

13. An apparatus for laying strip material onto a predetermined surface, said strip material being contained on a roll, means for supporting said roll in the apparatus in such manner as to rest upon the surface over which the apparatus is moved in the operation of laying said strip material, means in said apparatus supported on said roll for applying pressure thereto to facilitate the laying of said strip on said surface, means for applying an adhesive substance to that face of the strip arranged adjacent said surface to secure said strip thereto, other means for applying a suitable adhesive to the upper face

of said strip after it has been applied to said surface, means for movably supporting another roll of strip material in connection with the apparatus to be laid onto the first named strip in the progress of the apparatus over said surface, a tank arranged in the apparatus and forming a container for the adhesive substance employed, and means involving anti-frictional devices for supporting said tank upon said first named roll.

14. An apparatus for laying strip material onto a predetermined surface, said strip material being contained on a roll, means for supporting said roll in the apparatus in such manner as to rest upon the surface over which the apparatus is moved in the operation of laying said strip material, means in said apparatus supported on said roll for applying pressure thereto to facilitate the laying of said strip on said surface, means for applying an adhesive substance to that face of the strip arranged adjacent said surface to secure said strip thereto, other means for applying a suitable adhesive to the upper face of said strip after it has been applied to said surface, means for movably supporting another roll of strip material in connection with the apparatus to be laid onto the first named strip in the progress of the apparatus over said surface, a tank arranged in the apparatus and forming a container for the adhesive substance employed, means involving anti-frictional devices for supporting said tank upon said first named roll, and manually operated means for controlling the discharge of said substance onto the strip material of said first named roll.

15. An apparatus for laying strip material onto a predetermined surface, said strip material being contained on a roll, means for supporting said roll in the apparatus in such manner as to rest upon the surface over which the apparatus is moved in the operation of laying said strip material, means in said apparatus supported on said roll for applying pressure thereto to facilitate the laying of said strip on said surface, means for applying an adhesive substance to that face of the strip arrangement adjacent said surface to secure said strip thereto, other means for applying a suitable adhesive to the upper face of said strip after it has been applied to said surface, means for movably supporting another roll of strip material in connection with the apparatus to be laid onto the first named strip in the progress of the apparatus over said surface, a tank arranged in the apparatus and forming a container for the adhesive substance employed, means involving anti-frictional devices for supporting said tank upon said first named roll, manually operated means for controlling the discharge of said substance onto the strip material of said first named roll, and spreaders

arranged adjacent the discharges of said adhesive substance.

16. In apparatus of the class described involving means for supporting a roll of strip material to support and guide said roll in its movement over a predetermined surface, a tank movably supported in said means and arranged above said roll, an elongated nozzle discharge in communication with said tank and arranged above and adjacent said roll to discharge a liquid contained in said tank onto the strip material of said roll prior to the removal of said material therefrom, and a manually operated valve controlling the communication between said tank and said nozzle discharge to regulate the discharge of liquid from said nozzle.

17. In apparatus of the class described involving means for supporting a roll of strip material to support and guide said roll in its movement over a predetermined surface, a tank movably supported in said means and arranged above said roll, an elongated nozzle discharge in communication with said tank and arranged above and adjacent said roll to discharge a liquid contained in said tank onto the strip material of said roll prior to the removal of said material therefrom, a manually operated valve controlling the communication between said tank and said nozzle discharge to regulate the discharge of liquid from said nozzle, and another nozzle discharge in communication with said tank and through which the liquid contents thereof is adapted to be passed onto the upper face of the strip removed from said roll, and another valve in operative engagement with said manually actuated means for controlling said last named nozzle discharge.

46. In testimony that I claim the foregoing as my invention I have signed my name this 1st day of Aug., 1930.

SAMUEL S. ROBINSON.
